UNITED STATES PATENT OFFICE.

FRANK F. FORSHEE, OF FLINT, MICHIGAN, ASSIGNOR TO WESTINGHOUSE ELECTRIC
PRODUCTS COMPANY, A CORPORATION OF MICHIGAN.

ELECTRIC RANGE.

1,385,990.

Specification of Letters Patent.

Patented Aug. 2, 1921.

Application filed March 1, 1920. Serial No. 362,426.

To all whom it may concern:

Be it known that I, FRANK F. FORSHEE, a citizen of the United States, and a resident of Flint, in the county of Genesee and State of Michigan, have invented a new and useful Improvement in Electric Ranges, of which the following is a specification.

My invention relates to electrically-heated apparatus, and particularly to electric ranges, and it has for one of its objects to provide a unitary electric oven and a unitary electric stove, which may be so mounted, in interchangeable side-by-side relation on a supporting member, as to make either a left-hand or a right-hand range.

A further object of my invention is to provide an electric oven and an electric stove which may be completely manufactured at the shop without reference to each other, 20 may be shipped individually and may then be assembled on the supporting base to form either a right-hand or a left-hand range, as may be desired by the purchaser.

Heretofore, an electric range was completely assembled at the factory and shipped to the distributor or to the purchaser and it was impossible to reverse the relative positions of the oven and the stove on the supporting frame.

More specifically considered, my invention embodies a unitary electric stove member, a unitary electric oven, reversible electrical connecting means therebetween, and a supporting frame on which both the oven and the stove may be mounted in interchangeable side-by-side relation.

In the single sheet of drawings, Figure 1 is a view, in front elevation, of an electric range embodying my invention, with the 40 stove and the oven assembled to form a so-called left-hand range, and Fig. 2 is a view, in front elevation, of the same oven and stove assembled to form a right-hand range.

An electric oven 1 and an electric stove 2 are mounted adjacent to each other on a platform 3 which is, in turn, supported by a plurality of supporting members 4. A plurality of control switches 5 and an electromagnetically-operated switch 6 are located at the 50 front of the stove 2 and are used to control the supply of energy to the various heating elements of the oven and the stove.

The oven 1 is located on the platform 3 between the front and the rear leg support

brackets 4^a at the outer edge of the platform 55 and an angle-iron member 8 suitably secured to the platform 3 at substantially the middle of its length. Screws 7 through the brackets 4^a and a plurality of screws 9 through the vertical side of the member 8 60 serve to hold the oven in its operative position on the platform 3.

The stove 2 is secured to the platform 3 by means of a plurality of screws 10 which clamp a depending apron 11 at the front 65 of the stove 2 against the platform 3. A similar apron 11 is provided at the rear of the stove 2.

The upper part of the stove 2 and of the oven 1 are held in proper alignment by 70 means of a shelf back 12, which is provided with ornamental end pieces 13. Screws 14, through the end pieces 13, hold the outer ends of the top of the stove and the oven in proper operative engagement with the 75 shelf back. The inner ends of the top of the stove back and of the oven are further held in alignment by means of a small metal strap 15 and screws 16.

An extension shelf 17 is provided for the 80 stove and is detachably secured thereto in any well known manner.

As the control switch 5 and the electromagnetic switch 6, which control the heating element (not shown) in the oven 1, are 85 mounted at the front of the stove 2, suitable electrical conductors are provided to connect the control switches to the heating element in the oven 1. A terminal block 18 is provided in the rear wall of the oven 1, to which a 90 heating element (not shown) for the oven may be connected. A second terminal block 19 is provided, and two conductors (not shown) connect the terminals of this terminal block to two of the contact terminals of 95 a double-pole switch 20, only the operating handle of which is shown. The other two contact terminals of the switch 20 are operatively connected, by means of conductors (not shown) to the outer terminals on the 100 terminal block 18. A triple conductor cable 21 connects the switch 5 and the circuit-breaker 6 to the terminal blocks 18 and 19 and is located as follows: beginning at the rear of the switch 5 and the circuit-breaker 105 6, the cable runs to the rear and center of the stove 2, at which point the conductors pass through the rear wall through openings

2
in an insulating member 22 and then run, in a substantially horizontal position, across the back of the stove and the oven until the blocks 18 and 19 are reached. A terminal 5 cover 23 of substantially channel-section is mounted on the back of the stove, and two terminal covers 24 and 25, also of channel section, are mounted on the back of the oven to protect the conductors and the terminal 10 blocks. A wire cover 26, also of channel section, is provided to protect the cable 21 at the horizontal part of its length.

A control circuit, comprising a twin conductor cable 27, extends from the electro- 15 magnetic switch 6 to a third terminal block 28 which is mounted on the rear wall of the oven, and this control cable follows substantially the same path as does the cable 21. It may be pointed out that the insulat- 20 ing bushing 22 and the terminal blocks 18, 19 and 28 are located on the center lines of the stove and of the oven, respectively, for a purpose to be hereinafter set forth.

If it be assumed that the electric range 25 has been completely assembled as a left- hand range, as shown in Fig. 1, and that it is desired to reassemble it as a right-hand range, we may proceed as follows.

Remove the terminal covers 23, 24 and 30 25 and the wire cover 26 from the back of the range and disconnect the wires of the two cables 21 and 27 from the contact terminals on the terminal blocks 18, 19 and 28. Remove the screws 10 from the front 35 and the back of the stove and remove the stove bolts 14 from the shelf back 12. Remove the stove bolts 16 and the strap 15 and the extension shelf 17. The stove 2 may now be turned through an angle of 40 180° on a vertical axis, and the screws and stove bolts 10 may then be replaced. The relatively heavy and stiff cable 21 now extends away from the oven 1.

Now remove the screws 7 from the front 45 and the rear leg-support bracket and also remove the screws 9 which hold one end of the oven in operative engagement with the member 8. Then turn the oven through an angle of 180° on a vertical axis and replace 50 the screws 7 and 8.

The cables 21 and 27 may now be bent through an angle of 180° and again connected to the proper contact terminals on the terminal blocks 18, 19 and 28. As these 55 blocks are on the center line of the oven 1, no more than ordinary care need be used in bending the cables 21 and 27 to insure their extending to the contact terminals in the new side-by-side relation of the oven 60 and the stove. The terminal covers 23, 24 and 25 and the wire cover 26 may now be replaced in their proper operative positions on the back of the stove and of the oven.

Replace the shelf back 12 and the bolts 65 14 and the strap 15 and the bolts 16 and

the extension shelf 17 at the outer side of the stove 2.

The oven and the stove are now on re- 70 verse ends of the platform 3 and arranged to make a right-hand range, with the front of the complete range on the opposite side of the platform, and it is only necessary to turn the complete range through an angle of 180° to have its front on the same side as before. 75

I thus provide a unitary oven and stove which may be built individually at the factory, shipped separately and assembled at the purchaser's home, thus reducing considerably the expense of packing and of shipping. In case it is desired or becomes necessary to reverse a range, this may be easily and quickly effected. It may also be pointed out that a distributor may order a supply of stoves, ovens and supporting members 85 and may then assemble them to make either a right-hand or a left-hand range, as may be required by the purchaser.

While I have shown a specific embodiment of my invention, various changes may 90 be made without departing from the spirit and scope of my invention, and I desire that only such limitations shall be placed thereon as are imposed by the prior art or are specifically set forth in the appended 95 claims.

I claim as my invention:

1. An electric range comprising a sup- 100 porting member, an electrically heated oven, current conductors located in said oven, terminals for said conductors, an electrically heated stove, said stove and said oven being mounted in interchangeable side-by- side relation on said supporting member, and current conductors on said stove adapt- 105 ed to operatively engage said stove conductor terminals in either of the two relative positions of said stove and said oven.

2. In an electric range, the combination 110 with a supporting member, of an electrically-heated stove, an electrically-heated oven, both said stove and said oven having contact terminals mounted in spaced relation to each other on the backs thereof, and detachable electrical connections be- 115 tween said contact terminals, said stove and oven being adapted to be mounted in interchangeable side-by-side relation on the sup- porting member.

3. In an electric range, the combination 120 with a horizontal supporting means of sub- stantially rectangular outline, of an electrically-heated oven, an electrically-heated stove, current-controlling means for said oven and said stove mounted at the front 125 of said stove, contact terminals for said oven mounted on the rear thereof, and current-conducting means between said oven contact terminals and said controlling means on said stove, said conducting means be- 130

ing adapted for either left-hand or right-hand side-by-side location of said oven and said stove on said supporting means.

4. In an electric range, the combination with a supporting member, of an electrically-heated oven, an electrically-heated stove, and current-controlling means for both said stove and said oven located at the front of said stove.
5. In an electric range, the combination with a supporting member, of an electrically-heated oven, an electrically-heated stove, current-controlling means for both

said stove and said oven located at the front of said stove, contact terminals for 15 said oven located at the rear side thereof, current-conducting means connecting said controlling means and said terminals located on the back of said oven and stove, and covering means for incasing said current-conducting means. 20

In testimony whereof, I have hereunto subscribed my name this 25 day of Feb., 1920.

FRANK F. FORSHEE.
